UNITED STATES PATENT OFFICE.

FREDERICK J. ANTHONY, OF WICHITA, KANSAS, ASSIGNOR TO WESTERN IRON AND FOUNDRY COMPANY, OF WICHITA, KANSAS, A CORPORATION OF KANSAS.

WHEEL.

Application filed November 24, 1926. Serial No. 150,532.

This invention relates to power wheels and particularly to power wheels such as are used in connection with oil well rigs and the like. Specifically the invention relates to bull wheels, calf wheels, band wheels and the like. For the purpose of simplicity and clearness I will hereinafter refer to the invention as a calf wheel with the proviso that it is not limited in all its aspects to calf wheel construction. Calf wheels are usually made of wood, they get out of round, they warp and weave, and besides considerable skill is required to construct a bull wheel, calf wheel, or the like at the derrick.

My invention contemplates a built-up wheel for oil well rigs or the like which may consist mainly of metal which will not have excessive weight and which will not warp or weave in practice. The wheel may be completely constructed at the foundry and attached to its shaft at the rig.

The main object of the invention is to provide a novel hub structure whereby the wheel may be conveniently slipped over the end of the shaft and securely fastened thereto by bolts or other suitable fastening devices.

In order to understand the construction and advantages of this invention, reference should be made to the following description in connection with the accompanying drawings in which:—

Fig. 1 is a perspective view of a calf wheel constructed in accordance with my invention, applied to its shaft, certain parts being broken away.

Fig. 2 is a sectional view through the inner and outer hubs, part of the shaft being shown in elevation, and

Fig. 3 is a sectional view through a modified form of hub.

The shaft 1 is provided with gudgeons 2 and 3, the latter being on an inner hub member 4, fast to the end of the shaft 1. The inner hub 4 has an annular flange 5 with bolt openings 6 by means of which the outer hub of the wheel may be secured to the shaft. The outer end of the inner hub is provided with a spider 7 which carries the gudgeon 3.

The wheel is illustrated as comprising a slip-on outer hub of ring-form having bolt openings 9 adapted to align with the opening 6 in the inner hub 4 whereby the ring-shaped outer hub 8, having been slipped on

the cylindrical portion 10 of the inner hub may be secured to the flange 5 on the inner hub by the bolts 11. Fastening devices 10' may be employed to fasten the inner hub member 4 to the tubular shaft 1 so the hub member 4 will rotate with it.

The ring-shaped outer hub 8 is provided with an outstanding annular flange 12 located approximately midway between the ends of the outer hub. There are two sets 13 and 14 of tangentially disposed lugs, those on one side of the flange 12 alternating with those on the opposite side of the flange.

The lugs constitute seats for the ends of the spokes 15. The spokes are illustrated as commercial angles, one flange of each angle being fastened to a lug, the other flange lying against the face of the flange 12 so that the spokes will be rigidly held against twisting, and since they may resist torsional strains, tendency of the rim to weave or get out of round will be reduced to a minimum.

The rim of the wheel consists of the cant 16, on the opposite faces of which are the segmental plates 17 and 18 grouped together in circular series and fastened one to the other as well as to the cant, by fastening devices 19 and 20. Between complementary face plates are channel shaped tie-plates which not only tie the face plates together but also serve the purpose of tying or fastening the outer ends of the spokes to the rim. The spokes may be cut in appropriate lengths from commercial angle iron, the tie-plates 21 may be cut from commercial channels and the face plates may be cut in uniform segments from commercial sheets. The cant of the wheel may consist either of wood or iron and when the wheel is entirely constructed it will be rigid relatively light and durable.

It can be shipped to the derrick and there attached to the inner hub and shaft or the inner hub and shaft may be assembled with the wheel prior to shipment as best practice may dictate.

From the foregoing it will be apparent that the wheel may be inexpensively constructed, that it will have all the advantages of the ordinary wooden power wheel without any of its disadvantages and the hub of the wheel can be easily attached to the power shaft, that is to the inner hub member in a convenient manner.

In Fig. 3 I have shown the hub as applied to the drive end of the bull wheel con-

struction, the essential difference being that the inner hub member 25 is sleeved on the shaft 26 back from the end and supports the outer hub member which carries a guard. 5 The inner hub member is provided with a flange 27 to which the outer hub member 28 is fastened by bolts 29, long enough to extend through the outer hub member and be provided with nuts 30 and 31 between which the guard 32 is fastened, the guard 32 having a peripheral inturned flange 33 so that the guard will prevent the operator's clothes catching on the ends of the bolts as the shaft and wheel rotate. Of course, in the construction shown in Fig. 3, the gudgeon is not carried by the inner hub member but is on the end of the shaft as indicated at 34. In other respects, the hub structure shown in Fig. 3 closely follows the structures shown 10 in Figures 1 and 2.

What I claim and desire to secure by Letters Patent is:—

1. In combination, a shaft, an inner hub member fast to the shaft, a gudgeon on one 25 end of the inner hub member, a flange on the other end of the inner hub member, a wheel hub member sleeved on the inner hub member and fastening devices passing through the flange and through the second

mentioned hub member to secure the two 30 hub members together.

2. A power wheel comprising a cant, a hub having an outstanding flange intermediate its ends, face plates on opposite faces of the cant and spokes connecting the 35 face plates to the hub, the spokes comprising angles each having one flange fastened to a hub portion with the other flange in intimate contact with the flange on the hub, one-half of the number of spokes being located on each side of the flange, the spokes on one side of the flange alternating with the spokes on the other side of the flange. 40

3. A power wheel comprising a cant, a hub having an outstanding flange, face plates on 45 opposite faces of the cant arranged in circular series, tie members connected to and bridging the gap between complementary face plates, angle-shaped spokes secured to the hub, alternating spokes being on opposite sides of the flange, secured to the hub and fastened to the tie members, each spoke having a flange bearing against the outstanding flange on the hub and against one 50 of the face plates. 55

In testimony whereof I affix my signature.

FREDERICK J. ANTHONY.
